HIS ATTORNEY

UNITED STATES PATENT OFFICE

172,228

ICE-CREAM CARTON

Howard L. Franklin, Newark, N. Y., assignor to
Bloomer Bros. Company, Newark, N. Y., a corporation of New York

Application October 28, 1953, Serial No. 27,358

Term of patent 3½ years

(Cl. D58—12.6)

To all whom it may concern:

Be it known I, Howard L. Franklin, have invented a new, original, and ornamental Design for Ice-Cream Carton, of which the following is a specification, reference being had to the accompanying drawing, forming a part hereof.

Fig. 1 is a perspective, and

Fig. 2 a top plan view of an ice-cream carton embodying my new design.

I claim:

The ornamental design for an ice-cream carton, substantially as shown.

Certificate of Correction

Design No. 172,228

May 18, 1954

Howard L. Franklin

It is hereby certified that error appears in the above numbered patent requiring correction as follows:

In the grant, line 15, for "THREE and ONE-HALF" read *SEVEN*; in the heading to the printed specification, line 7, for "3½ years" read *7 years*; and that the said Letters Patent should be read as corrected above.

Signed and sealed this 13th day of July, A. D. 1954.
